UNITED STATES PATENT OFFICE.

VICTOR BOUCHARDON, OF PARIS, FRANCE.

SENDER FOR HERTZIAN WAVES UTILIZING POLYPHASE GENERATORS.

1,302,129.

Specification of Letters Patent. Patented Apr. 29, 1919.

Application filed July 27, 1914. Serial No. 853,370.

To all whom it may concern:

Be it known that I, VICTOR BOUCHARDON, a citizen of the French Republic, residing at Paris, in the Republic of France, have invented certain new and useful Improvements in Senders for Hertzian Waves Utilizing Polyphase Generators, of which the following is a specification.

This invention relates to a sending device for producing damped Hertzian waves, in which the waves are produced by the oscillating discharge of a battery of condensers traversing a self-induction which forms the primary of a transformer of oscillations, whose secondary is in series in the antenna. The battery is charged by a polyphase generator of low periodicity, either directly or through the intermediary of step-up transformer. With this object in view the battery is composed of a number, equal to the number of the phases, of condensers of equal capacities which are connected in series so as to constitute a closed polygon whose apexes are connected with the terminals of the generator. During one period the tension is successively a maximum at the terminals of each of the capacities of the polygon.

This connection has already been proposed for different devices which present the general characteristic of having as many circuits of discharge as there are phases, the secondaries of the different transformers of oscillations being connected in series with the antenna. These devices increased the number of pieces of apparatus and complicated the plant; besides, the current of the antenna had to traverse continuously two inactive secondaries.

This invention is characterized by the use of a single high-frequency transformer whose secondary circuit is inserted in the antenna and whose primary circuit is connected with the capacity to be discharged by a special rotary spark gap.

This spark gap is constructed in such a manner that each condenser of the polygon has as many discharges per second as the alternator has alternations. The total number of discharges per second is therefore equal to twice the product of the number of cycles by the number of phases.

For example:—a three-phase alternator

of 50 periods will give 300 discharges. Between two discharges the charge takes place always in the same part of the curve of electromotive force of the generator. If, further, the frequency of the charging current is regulated so that the tension at the terminals of the condenser be a maximum at the moment of the discharge a stable load is obtained giving a succession of regularly spaced discharges which all use the same electrostatic force.

This invention therefore permits of obtaining a musical emission with alternators of rather low periodicity which are easily found in the market and which have a greater efficiency than the single-phase generator of singing frequency (up to 2,000 periods) used at present.

In the accompanying drawing a form of application of the invention is shown by way of example:

Figure 1 is a diagram of the connection of the sender applied to a three-phase alternator.

Fig. 2 shows the curve of the electromotive forces applied at the terminals of the different condensers.

Figs. 3, 4 and 5 show diagrammatically a form of construction of a rotary spark gap suitable for carrying out this invention for three-phase alternators having 4 poles, and Figs. 6, 7 and 8 a like form of construction for a spark gap for a 6 pole three-phase alternator. Figs. 9, 10 and 11 and Figs. 12, 13 and 14 show a second form of construction of the rotary spark gap for 4 and 6 pole three-phase alternators respectively.

The Figs. 15, 16 show the same two solutions in the general case of a three-phase alternator with 2 p. poles.

In Fig. 1 A is a three-phase alternator; from the terminals of its three phases wires start, which, through regulating and protecting self inductances S and through three transformers T, end at the apexes C₁, C₂, C₃ of a circuit in triangle, in the sides of which three condensers C', C'', C''' are inserted. The three wires continue from the apexes C₁, C₂, C₃ and are connected with the three points 1, 2, 3 of a fixed circle; from two points 4 and 5 of the same fixed circle start two wires which go to a transformer of oscillations 6, which may be of the Oudin

type for example; that is to say, one consisting of a single winding, one of the two connecting wires from the closed circle terminating at a fixed point 8 at the end of the 5 winding or self inductance and the other having a movable contact 9 at a variable point of the self inductance. The two ends of the self inductance 6 are connected with the antenna 7 and with the earth 10. The 10 spark gap consists of a rotating part R keyed on the shaft of the alternator and turning in the fixed circle to which the different wires are connected and it carries tips and convenient connections as will be hereinafter explained, so that at the required moment the 15 two points 1 and 2 are connected with the points 4 and 5, the condensers C', C" situated between C₁ and C₂ being short circuited through the transformer 6 whereby an oscillating 20 discharge is produced and a wave-train is emitted by the antenna 7. The three curves C₁—C₂, C₂—C₃, C₃—C₁ of Fig. 2 represent for each moment the electromotive 25 forces used for charging the condensers C'', C'', C', the axis O—X being the axis of time.

In the first form of construction of the special rotating spark gap shown in Figs. 3, 4 and 5 the points 1, 2 and 3 of the fixed circle with which the three phases are connected are situated at 120° from each other. The tips 4 and 5 with which the ends of the 30 transformer 6 are connected are situated at 30° at both sides of the point 1, for example, and are connected with the tips 4', 5' respectively which are situated at 30° from the tips 4 and 5. The rotating part R consists of a disk which has four groups, each having two tips r₁, r₂, r₃, r₄, r₅, r₆, r₇, r₈. The two tips of each group are situated at 30° from each 35 other and are connected together, the opposite groups being also connected with each other, for example, r₁—r₂ with r₅—r₆, etc. If at the time O the tip r₁ of the movable circle passes before tip 1 of the fixed circle 40 and if at this moment the tension at the terminals of C'' is a maximum, the two apexes C₁, C₂ are connected with one another through the transformer 6 by the following circuit:

$$50 \quad 1-r_1-r_2-5-6-4-4'-r_8-r_4-2,$$

the condenser C'' sending an oscillating discharge through the transformer 6.

55 In the position shown in Fig. 4 the rotating part R has turned through 30° and the tip r₁ is in front of the tip 5. Fig. 2 shows that at this moment the tension at the terminals of C' is maxima. In fact, as the generator has four poles there will be four alternations at every revolution, the distance between two apexes of successive phases o—12 (Fig. 2) will be $\frac{1}{2}$ of a revolution, that is to say corresponding with a rotation of 30°.

In the position Fig. 4 the points 2 and 3 65 are connected by the circuit:—

$$2-r_3-r_8-4-6-5-r_1-r_6-3.$$

The condenser C' which is at the maximum tension will therefore produce an oscillating discharge corresponding with a new wave-train.

By a new rotation of 30° the rotating part R of the spark gap will arrive at the position shown in Fig. 5 so that the tip r₁ will stand opposite the point 5¹ connecting the tips 1 and 3 that is to say producing the discharge of the condenser C'' which at this moment is at its maximum tension and so forth. There will be produced twelve sparks at 80 every revolution of the spark gap, that is to say of the generator.

In the form of construction shown in Figs. 6, 7 and 8 and relating to a three-phase generator with six poles, the movable part R comprises twelve tips connected in pairs and arranged in two groups as shown in the drawing. In Fig. 4 the discharge is produced between 1 and 2 in passing through the circuit:—

$$90 \quad 1-r_1-r_2-5-6-4'-r_{12}-r_3-r_4-2.$$

In Fig. 7 the discharge is produced between 2 and 3 by the circuit:—

$$2-r_3-r_{12}-4-6-5-r_1-r_{10}-3.$$

In Fig. 4 it is produced between 3 and 1 by the circuit:—

$$3-r_9-r_{10}-r_1-5'-6-4-r_{11}-r_{12}-1.$$

In the most general case of the same solution illustrated in Fig. 15 for a three-phase generator with 2 p. poles, the position of the tips on the fixed part and on the turning part expressed in angular distances are the following:—

$$100 \quad 1 \ 2 = I \ 3 = \frac{4 \times 120^\circ}{p}$$

$$1 \ 4 = 4 \ 4' = 1 \ 5 = 5 \ 5' = \frac{120^\circ}{p}$$

The movable part R will comprise 4 p. 110 tips the distance between successive tips being alternately $\frac{2}{p}$ and of $\frac{2 \times 120^\circ}{p}$. The tips at a distance apart of $\frac{120^\circ}{p}$ will be arranged in pairs as shown in the figure; all the groups of two tips of even numbers will be electrically connected in one polygon and all the groups of odd numbers will be connected in another polygon insulated from the first polygon.

A second form of construction of the rotating spark gap is shown in Figs. 9, 10 and 11 for a generator with 4 poles.

The apexes of the triangle of the condensers are connected as above with the tips 1, 2, 3 placed on the fixed circle at 120° from each other; the tips 4 and 5 are connected as

above with the oscillator 6; the tips 4' and 5' are connected with one another as are 4" and 5". The angular distances of these different tips are the following:—

$$\begin{aligned} 1' 2' &= 2' 3' = 3' 1' = 120^\circ \\ 2' 4' &= 2' 5' = 45^\circ \\ 3' 4' &= 3' 5' = 1' 4'' = 1' 5'' = 45^\circ \\ 5'' 4' &= 5' 4' = 5' 4'' = 30^\circ \end{aligned}$$

The rotating part R comprises four groups of 5 tips which are connected with one another in the same group: the groups are mounted on the turning part R from 90° to 90°. The tips of the same group are at a distance of 15°. Fig. 9 shows the position of spark gap at the moment when the tension is a maximum between the points 1 and 2; the discharge follows the path:

$$1-5''-4''-5'-4'-5-6-4-2$$

The spark from the discharge is divided into 8 sparks in series. Fig. 10 shows the position of the spark gap after it has turned through $\frac{1}{12}$ revolution; at this moment the tension is maxima between the tips 2 and 3 and the spark follows the path:—

$$2-5-6-4-5''-4''-5'-4'-3$$

Fig. 11 shows the spark gap in the position which it occupies after $\frac{1}{12}$ of a revolution; the tension is a maximum between the tips 3 and 1; the spark follows the path:—

$$3-5'-4'-5-6-4-5''-4''-1$$

and so on, one spark being produced at every twelfth of a revolution.

The Figs. 12, 13 and 14 show the application of this second form of the spark gap in the case of a three-phase generator with six poles, the movable part comprising six groups of five tips at a distance apart of 10°, the groups being at a distance apart of 60°. The Figs. 12, 13 and 14 correspond respectively to the positions which the spark gap occupies when the tension is a maximum between the tips 1—2, 2—3 and 3—1 respectively.

The Fig. 16 illustrates the arrangement of this spark gap in the general case of a three-phase generator with 2 p. poles.

The movable part R comprises 2 p. groups of 5 tips. In the same group the tips are at a distance apart of $\frac{30^\circ}{p}$ and the groups are at a distance apart of $\frac{120^\circ}{p}$ —they are insulated from one another. The fixed part comprises eleven tips arranged along a circle and at the following angular distances apart—

$$1' 2' = 1' 3' = \frac{240^\circ}{p}$$

$$1' 4' = 1' 5' = 2' 4' = 2' 5' = 3' 4'' = 3' 5'' = \frac{90^\circ}{p}$$

The tips 4" and 5" (which do not exist in

the case of a generator with 4 poles) close the circuit and stand at a distance apart of 65

$$5' 4''' = 4'' 5''' = \frac{60^\circ}{p}$$

It will be easily understood that the operation of this spark gap is exactly similar 70 to the generalized cases of 4 and 5 poles which have been hereinbefore explained.

There could be imagined a great number of rotating spark gaps having similar arrangements and producing the same effect; 75 the only condition which must be always fulfilled is that the spark gap revolve at the same speed as the generator; it could be mounted at the end of the generator shaft. The spark gap could even be moved by a 80 synchronous motor owing to the comparatively low frequency of the generator.

I claim:—

1. In apparatus for the production of damped Hertzian waves the combination of 85 an n -phase alternating current generator, a battery of n -condensers of equal capacity connected in mesh, conductors connecting the n terminals of the generator with the n corners of the mesh connected condensers 90 and conductors connecting the n corners of the mesh connected condensers to n points of a spark producing device, connectors connecting two points of said spark producing device with the primary of an oscillation 95 transformer, and means forming a part of the spark producing device for successively effecting discharge through the primary of the transformer of the condensers at the moment at which their terminals have the 100 maximum potential difference.

2. In apparatus for the production of damped Hertzian waves the combination of 105 an n -phase alternator, n mesh connected condensers of equal capacity and connected to said alternator, and a transformer, a rotary spark gap device comprising n fixed discharge points to which the corners of the condenser connections are connected, two additional fixed discharge points connected 110 to the terminals of the primary of the transformer, and a member rotating synchronously with the alternator and provided with interconnected discharge points so arranged as to successively discharge the individual condensers through the primary of the transformer at the moment of maximum potential difference between the condensers. 115

In witness whereof I have hereunto set my hand in the presence of two witnesses.

VICTOR BOUCHARDON.
